UNITED STATES PATENT OFFICE

VICTOR R. DESPARD AND HANS C. R. POPP, OF VALPARAISO, INDIANA, ASSIGNORS TO
MCGILL MANUFACTURING COMPANY, A CORPORATION OF INDIANA

CONTACT-TERMINAL MOUNTING

Application filed October 16, 1925. Serial No. 62,835.

Our invention relates to means for mounting contact terminals and more particularly to means for mounting the stationary contacts in a switch mechanism.

5 It is a purpose of our invention to provide means for mounting contact terminals on a base member whereby the same are held from movement in all directions. Said base member is preferably an insulating body portion 10 and is provided with a suitable depression or hollow for accommodating the contacts. Means is provided on each of said contacts for holding the same in fixed position relative to the base member and to each other. Said 15 means preferably comprises an extension that is seated in a groove and the body portion is provided with a cover member that closes said groove to hold said extension therein.

More particularly it is a purpose of our 20 invention to provide a combination contact member and wiring terminal that is so related to an insulating body portion in which the contact is seated and said insulating body portion being so formed that when the combined 25 contact and terminal member is in engagement therewith, the same will be held against movement in all directions provided the above mentioned cover member is in place. The combined contact and terminal members preferably each comprise a contact making portion, a wiring terminal portion and a connecting portion, the connecting portion lying in a plurality of planes, preferably extending 30 at right angles to each other, and the insulating body portion being provided with a 35 recess for receiving each of said wiring terminal portions which also accommodates the respective conductor connected with said wiring terminal portion in said recess. The depression for receiving the contact and the groove receiving the connecting portion are 40 so related that shoulders are provided on opposite sides of the groove engaging with the offset portions of the contact member extension or connecting portion so as to prevent 45 movement of said contact members in a plurality of directions.

Other objects and advantages of the invention will appear as the description of the accompanying drawings proceeds. However,

we desire to have it distinctly understood that we do not intend to limit ourselves to the exact details shown or described, but that we intend to include as part of our invention all such obvious changes and modifications of 55 parts as would occur to a person skilled in this art and as would fall within the scope of the claims.

In the drawings:

Fig. 1 is a view partly in elevation and 60 partly in section of a switch mechanism employing our improved contact terminal mounting;

Fig. 2 is an inside face view of the insulating body portion of said switch mechanism 65 showing certain of the contact terminals in position therein; and

Fig. 3 is a perspective view of one of the contact terminals.

Referring in detail to the drawings, our 70 improved contact terminal mounting is shown as being applied to a switch mechanism having a body portion 10, a cover member 11 and an insulating gasket member 12 positioned between said cover member and said body 75 portion. In the form shown, the switch mechanism comprises a rotatable contact carrying member 13 upon which suitable contacts 14 are mounted which is rotated by means of the operating member 15. The contacts 14 co- 80 operate with a plurality of contacts 16 and 16' which are mounted on suitable seats 17 provided on a shoulder in the central depression 18 provided in said body portion 10 which accommodates the rotatable contact 85 carrying member 13 as well as the stationary contacts 16 and 16'. The contacts 14 engage with the contacts 16 and 16' in any suitable manner upon rotation of the rotatable contact carrying member 13. 90

Each of the contacts 16 is made as shown in Fig. 3, the arcuate contact making portion 16 being provided with an upward extension 19 extending substantially at right angles to the portion 16, a transversely extending portion 20 extending substantially at right angles to the portion 19, a depending portion 21 extending substantially at right angles to the portion 20 and substantially parallel to the portion 19 and a sleeve-like terminal portion 100

22 formed at the end of the depending portion 21 which is adapted to receive the conductor 23 provided with an insulating covering 24 and which is secured thereto by means of solder indicated at 25, the soldering being readily accomplished by a dipping operation. The portion 21 and the sleeve-like portion 22 are seated in a recess 26 in the body portion 10, there being four of such recesses shown 10 in the embodiment of the invention illustrated. An opening 27 extends through the rear face of the body portion 10 from the recess 26 for easy access to the ends of the conductors 23 and the wiring terminals 22 for testing purposes.

15 The shallow grooves 28 connect the recesses 26 with the central depression or hollow 18 of the body portion 10, there being an annular shoulder 29 formed in said body portion between the shoulder 17 and the shallow grooves 28 against which the portion 19 of each of the contacts 16 rests and there being a shoulder 30 formed by the wall connecting the deep recess 26 with the shallower groove 28. 20 25 against which the portion 21 of one of the members 16 engages, it being obvious that each of the grooves 28 and recesses 26 are so related as to provide such shoulders for engagement by the portions 21.

30 Suitable screws 31 extend through the openings 32 for holding the cover member 11 in position on the body portion 10 and when said cover member is in position on said body portion, the insulating member 12 will engage 35 with the portions 20 and the portions 20 of the contact members will be firmly held in the grooves 28 with the offset portions 19 and 21 in engagement with the shoulders 29 and 30, thus preventing movement in any direction of the contact 16. The contact 16' is 40 made in exactly the same way except that it has an extension 33 on the contact making portion thereof. The extension 20 thereof is provided with the offsets to hold the same 45 from movement in all directions and is seated in its groove 28 in the same manner as are those of the contact 16 and the same is provided with a wiring terminal in the same manner as the other contacts.

50 Having thus described our invention, what we desire to claim and secure by United States Letters Patent is:

1. In a device of the character described, a hollow insulating body portion, a cover 55 therefor and contacts in said body portion, said body portion having grooves therein extending from the hollow thereof and said contacts having extensions thereon seated in said grooves and clamped between said body portion and said cover to hold said contacts in substantially fixed position in said body portion.

2. In a device of the character described, a hollow insulating body portion, a cover 60 therefor and contacts in said body portion,

said body portion having grooves therein extending from the hollow thereof and said contacts having extensions thereon seated in said grooves, cooperating means on said body portion and said extensions holding 70 said extensions from longitudinal movement in said grooves, said extensions being mounted between said body portion and said cover to hold said contacts in substantially fixed position in said body portion.

3. In a device of the character described, a hollow insulating body portion having recesses therein spaced from the hollow thereof, and grooves extending from each of said recesses to said hollow, there being shoulders 80 at opposite ends of said grooves, and contact members in said hollow having holding portions extending into said grooves and recesses and having offsets extending around said shoulders, and means for confining said holding portions in said grooves.

4. In a device of the character described, a hollow insulating body portion having a groove therein communicating with said hollow, a contact in said hollow having a holding portion seated in said groove, cooperating means on said insulating body and said contact for holding said portion from longitudinal movement in said groove and means for confining said portion in said groove.

5. In a device of the character described, a hollow insulating body portion having a groove therein, a recess in said body portion, said groove communicating with said recess and with said hollow, a contact in said hollow having a portion seated in said groove and extending into said recess, cooperating means on said insulating body and said contact for holding said portion from longitudinal movement in said groove and means for confining said portion in said groove.

6. In a device of the character described, a body portion having a depression therein, a contact in said depression, a recess spaced from said depression, and a groove shallower than said depression and said recess defining shoulders at opposite ends thereof, a portion of said contact resting in said groove and offset around said shoulders, and means for holding said portion in said groove.

7. In a device of the character described, a hollow insulating body portion having a groove therein communicating with said hollow, a contact in said hollow having a holding portion seated in said groove, cooperating means on said insulating body and said contact for holding said portion from longitudinal movement in said groove, a cover confining said portion in said groove, and means for insulating said cover from said contact.

8. In a device of the character described, a body portion having a depression therein, a contact in said depression, a recess spaced from said depression, and a groove shallower than said depression and said recess defining

shoulders at opposite ends thereof, a portion of said contact resting in said groove and offset around said shoulders, and a cover for confining said portion in said groove, said cover extending over said recess.

5 9. In a device of the character described, an insulating body portion having a depression therein, a series of contacts seated in said depression, said body portion having a plurality of grooves therein extending outwardly from said depression, extensions on said contacts seated in said grooves, a cover for clamping said extensions in said grooves to hold said contacts in predetermined spaced relation in said depression, and wiring terminals on said extensions mounted in recesses in said body portion.

10 15 In witness whereof, we hereunto subscribe our names this seventh day of October, A. D., 1925.
